 Corporation, Cleveland, Ohio, a corporation of
 New Jersey

Application June 12, 1946, Serial No. 676,261

2 Claims. (Cl. 122—498)

1

This invention relates to furnace doors, especially closures for furnaces of the types used in the manufacture or alloying of steel and other metals. In an important specific aspect the invention is designed to provide an improved and long-lived door construction for open hearth furnaces.

Because of the excessive heat and other unusually severe conditions encountered in steel furnaces of the open hearth type, difficulty has arisen in providing doors that will not break down frequently. Charging doors have been proposed or made with various arrangements of water containers, sometimes in combination with a lining of refractory brick or the like, but structural failures have been frequent, necessitating constant servicing and often entire replacement of the door after only a short period of use. Both the high temperatures and the extraordinary expansions and contractions arising between successive heats of the furnace tend to warp the door or to break its water connections or to open seams in the water tank or tanks, especially at corner welds. Furthermore, even though the door is lined with refractory material, conditions are such that the refractory breaks or spalls, and falls out, or often actually melts out. In consequence, it has been found that doors of the described type will usually not last for more than 10 to 15 heats and then they must be removed and relined and have any leaks welded. As a result, considerable delay is caused in furnace operations, or if attempt is made to repair the door while the furnace is functioning, the physical hazard to the workmen is considerable, in view of the tremendous heat.

Still further difficulty has been encountered in the circulation of water through tanks or cooling systems of the prior types of door, in that sediment tends to collect in the bottom, impairing or nullifying the cooling effect so as to result in burn-throughs, and similar consequences occur because of air or other gas released by the water and collecting at the head of the tank, sometimes forming an air lock that impedes circulation and, in any case, resulting in overheating in localities where the water is displaced by air or gas.

Thus an important object of the invention is to provide a furnace door of the liquid-cooled

2

type which will stand up longer in operation and which at the same time is of relatively simple construction. Further objects are to provide a door structure for open hearth furnaces and the like wherein positive and vigorous circulation of water is assured practically throughout the area of the door, wherein collection of sediment or of quantities of gas or air is minimized, and wherein various cooperating elements may be individually replaced without materially impairing the structural integrity of the remainder of the door. Another object is to provide a furnace door of the stated character, including novel and improved means for keeping a refractory material in place or at least in protective relation to cooling conduits, even though the temperature may be sufficient to melt such material. A still further object is to provide a door of the stated kind, wherein severe expansion and contraction of metal parts may take place without appreciable tendency to open seams or crack or warp the structural elements, a special object being to provide a door construction free of corner welds or like seams.

To these and other ends, including objects hereinafter apparent or otherwise incidental to the practice of the invention, and particularly including the provision of a door structure that may be used for a great number of successive furnace heats without need of repair or replacement, a particularly advantageous embodiment of the invention is described herein and shown in the accompanying drawings, by way of illustrative example. It is believed that the principles of the invention will thus be made clear and the susceptibility of the device to modification in various respects will likewise become apparent to those skilled in the art.

Referring to the drawings:

Figure 1 is an elevational view of the door, seen from its inside face, with certain portions in vertical section;

Fig. 2 is a section on line 2—2 of Fig. 1 but with the refractory material omitted for the sake of clarity;

Fig. 3 is an enlarged plan view, i. e., of the top of the door;

Fig. 4 is an enlarged end elevation as seen from the left hand side of Fig. 1;

Fig. 5 is an enlarged section on line 5-5 of Fig. 1; and

Fig. 6 is an enlarged end elevation at the right hand side of Fig. 1.

The specific device shown in the drawings is intended as a charging door for an open hearth furnace and is mounted to be raised vertically on the front of the furnace, as by means of the supporting plates 20, 21, 22, having holes to receive suitable studs and linkage connected to suitable counterweights above the furnace opening, by which the door is supported. It will be understood that the furnace and the door supporting and operating mechanisms may be of known, conventional type, and are therefore not illustrated.

The door itself comprises a generally rectangular line of pipe designated 24, constituting the periphery of the structure, and a sinuous line of pipe generally designated 25, that distributively fills the space within the rectangle and includes a vertical array of horizontal pipe sections generally designated 27, spaced from each other and connected at alternate ends. In the device shown, the outer or peripheral line of pipe comprises four straight sections 28, 29, 30, 31, joined at their ends by 90° L's of pipe butt-welded to the straight sections as shown. Thus a curved L 33 joins the top section 31 and side section 28; a similar curved L 34 joins the side section 28 and bottom section 29, but in this instance has a sidewise-opening port or coupling portion formed or welded therein at 35, the opening being normally closed by screw plug 36, which is adapted to be removed for draining and cleaning the cooling system. Similarly, sections 29 and 30 are joined by a curved L 37, and sections 30 and 31 by a similar L 38, which is formed or otherwise designed to constitute a T element, providing an opening or pipe coupling extension 40 directed outwardly of the front of the door.

The straight sections 27 of the sinuous line of pipe within the outer rectangle are preferably flattened vertically throughout nearly all of their length, as shown in Figs. 1 and 5, so as to have a horizontal dimension substantially larger than the vertical dimension. The ends of the sections can be round, however, so as to be joined by U-shaped coupling elements, or curved 180° L's 42. Although the number of straight sections 27, i. e., the number of horizontal passages in the sinuous line, may vary with the size and other requirements of the particular door, there ordinarily should be at least several, and preferably a multiplicity of such sections, for example seven as shown in the drawings. The uppermost section 27a is welded at one end to a 90° L, turned upward, which in turn is welded to a coupling length of pipe 44. The pipe section 44 extends vertically through the upper peripheral pipe section 31, being of smaller outside diameter than the inside diameter of the section 31 and being welded in watertight relation in appropriate holes bored in the latter. The opposite, round end of the flattened section 27a is welded to a 180° L 42 which in turn is welded to an end of the next lower horizontal section 27b, the latter being at its opposite end joined by a similar L to the succeeding section below, and so on, whereby a continuous passage for coolant is provided back and forth horizontally across the door through the desired multiplicity of conduit elements.

The lowermost horizontal section 27d at its

left hand end as seen in Fig. 1 is welded to a 90° elbow 46 turned downwardly, from which the line of pipe continuing the sinuous unit extends into the lower peripheral section 29 and then curves around and passes up centrally of the side section 30 and finally curves around in the L 38 into a conforming opening in a baffle or wall 47 which otherwise blocks the outer pipe structure at the joint between the L 38 and the top section 31. It will be understood that the vertically extending length of pipe 48 that goes up through the outer section 30 is, like the other parts of the sinuous pipe assembly, of substantially smaller diameter than the line constituted by the members 31, 30 and 38, whereby a passage for coolant is provided around the outside of the section 48 as well as within it. It will also be appreciated that the bends in the section 48 are provided by L's butt-welded to straight lengths or to each other, as in other portions of the pipe structure, although for clarity these welded joints are not specifically indicated in the drawings. The projecting outlet 40, which communicates with the interior of the L 38 but is not directly connected into the section 48, is butt-welded to a sidewise turned 90° L 50, in turn secured to a coupling section 51.

The outer face of the door comprises a flat plate 53 of generally rectangular configuration conforming with that of the outer pipe assembly 24, welded tangentially to the latter throughout its length. Secured by welding to the inner face of the plate 53 are a multiplicity of shelf-like projecting pieces 54, in turn welded along the underside of their outer edges, to the upper surfaces of the flattened pipe sections 27. The supporting shelves 54 are advantageously provided in sufficient number to constitute a secure mounting for the central pipe assembly; thus in the illustrated arrangement there are three such shelves regularly spaced along the upper side of each horizontal pipe length 27, except at the central parts of the lowermost sections 27c and 27d, as presently explained.

Charging doors for open hearth furnaces are usually provided with a small aperture, sometimes called a wicket hole, through which the interior of the furnace may be inspected or access may be had for tools or instruments, without opening the door itself. In the present construction, cooling means are provided for such hole, economically in cooperation with the flow of coolant through the sinuous length of pipe that distributively occupies the major area of the door. The wicket hole structure comprises concentric hollow cylinders 55 and 56, which may actually be sections of pipe of respectively different diameters, traversing the door on a horizontal axis in the vicinity of the centers of the lower pipe sections 27c and 27d. The outer plate 53 is pierced in conformity with the outermost tubular member 56 and is welded thereto, and the space between the tubular members is closed at each face of the door by an annular plate 57 welded around its outer and inner circumferences to the inner and outer surfaces of the pipe sections 56 and 55, as shown in Figs. 1 and 5. The ring-shaped jacket thus defining the wicket hole intersects the horizontal pipe sections 27c and 27d, and to effect such intersection the last-mentioned pipes have a center portion or length cut out of each in conformity with the curved outer wall 56 of the wicket hole jacket. The wall 56 is pierced in conformity and for communication

with the curved openings or cross-sections thus effected in the pipes 27c and 27d, and the joints at all places are welded watertight.

Thus the section 27c actually consists of two successive lengths connected in opposite openings near the top of the wicket hole jacket so that the latter is part of the coolant path of the pipe, and a lower coolant path is similarly provided by the two parts of section 27d opening into the lower part of the jacket wall 56. Since it is preferable to avoid by-passing water flow from the U-bend between pipes 27c and 27d, the described paths are separated by blocking plates 60, 61, disposed in the annular space between members 55 and 56 and extending from the front to the rear face of the door at a level approximately that of the lower wall of the pipe section 27c. The inside surface of the wicket hole may have the usual tool rest or reinforcing piece, for instance constituted by a 90° segment of a pipe of conforming shape 64, welded on the member 55 as shown.

To promote heat transfer and exchange, and to cooperate in retaining the refractory material in place, the inside of the plate 53 carries a multiplicity of projecting studs 65. These studs, for example extending almost to the plane of the further sides of the flattened sections 27 as shown, can be arranged in a plurality of rows between the pipes 27 and also in the similar spaces between the sinuous unit and the larger peripheral unit 24.

The entire space bounded by the peripheral unit and not otherwise occupied by elements described above, is filled with refractory material 68. Although a variety of refractories may be employed, 35 chrome ore prepared in an originally plastic condition is a useful example of such material, and also a somewhat similar composition produced under the trade name "Krome-Neutragrog." Thus in building the door the entire assembly of pipes, backing plate 53, and studs 65, may be fastened together, and then the plastic refractory material, for example in a stiff aqueous paste, is rammed into the space, preferably until it is at least flush with the further sides of the flattened horizontal pipes 27 as shown in Fig. 5, or even covering them, e. g., up to a plane tangent to the peripheral unit 24. For the usual type of furnace, the door advantageously occupies an area larger than that of the opening to be covered, and thus at least a substantial part of the breadth of the peripheral pipe 24 overlaps the door frame of the furnace structure when the door is closed.

In practice a liquid coolant, such as water, is introduced under pressure through the inlet pipe 44 and withdrawn through the outlet pipe element 51. The circulation is preferably effected under considerable pressure by a pump or other means (not shown), the path of the water being as illustrated by the arrows, i. e., entering the inlet 44 and then following the sinuous path including the horizontal pipe sections 27 in succession. As the water traverses the section 27c it passes through the upper part of the annular space for cooling the wicket hole, then continues around the 180° L and flows back in section 27d where it similarly traverses the lower part of the wicket hole jacket. Passing into the left hand part of section 27d, the water then travels through the L 46 and on into the upwardly extending pipe section 48 (which is concentrically disposed in the section 30), and thence flows into the surrounding rectangular pipe assembly, from the opening in the wall 41. The coolant then circulates completely around the peripheral path 24,

there being ample space for flow around the outside of pipes 44 and 48, and finally discharges through the outlet fittings 40, 50 and 51.

It will be observed that a single continuous path is provided for circulation of water, through the central and peripheral sections in succession. According to present preference the line of flow traverses the central portion first, where the heating effect is greatest and maximum heat exchange or cooling is desired, it being thus feasible to have a lower velocity of flow, by virtue of the larger cross-section, in the outer pipe system 24. At the same time, the wicket hole is effectively water-jacketed by a structure forming part of the same continuous path of flow, so that this exposed portion of the door is efficiently cooled.

As will now be understood, actual connections for water supply and discharge may be made with appropriate flexible or jointed pipe, not shown. It may also be noted that while a variety of types of components may be used in the present invention, including various diameters and thicknesses of pipe and different pipe materials, 25 eminently satisfactory results have been obtained in a door for an open hearth furnace utilizing steel pipe of $\frac{1}{2}$ inch wall thickness, the outer pipe section 24 having an inside diameter of 6 inches and the central length of pipe having, in its circular configuration, an inside diameter of 3 inches, the flattened sections 27 conveniently having inside horizontal and vertical diameters of about $3\frac{3}{4}$ inches and 2 inches respectively.

To avoid possible formation of a pocket of air or gas in the corner of the L 38 adjacent to the baffle 47, the latter is pierced by a small hole 70 near its upper side. For similar purposes, the baffles 60 and 61 in the annular wicket hole jacket may be pierced by like holes, of small diameter, e. g., of the order of less than $\frac{1}{2}$ inch. Although these vent holes in the baffles 47, 60 and 61 may effect some small return or by-pass flow, the amount of the latter is relatively insignificant, and at the same time effective means is provided to relieve any air or gas bubbles that might otherwise tend to accumulate at these localities.

The operation of the door should now be self-evident, in that a continuous circulation of water from the inlet and through the successive pipe sections to the discharge is afforded. A notable advantage of the structure is that it removes heat more rapidly than prior types of door mentioned hereinabove, and likewise prevents the settlement of sediment at any point. The circulation of coolant is in effect a forced feed, pressure type, in advantageous comparison with the commonly used older door arrangements wherein the circulation was essentially a gravity or thermal flow, by drift of the water upward in a tank or waterbox. In the present structure the comparatively small water passages have a tendency to cause turbulent flow and thus to carry along any particles of dirt that might otherwise tend to settle. There are no relatively stagnant localities or traps, either for settlement of mud or for the collection of air, and in consequence all the metal parts are effectively cooled without danger of local overheating and consequent burn-through.

A further advantage of the illustrated device is that the center section, embodying the sinuous length of pipe, is in effect independently supported and thus separately replaceable; if after long use the section leaks or the pipes are found

to have burned thin, this part can be easily and inexpensively replaced. Furthermore, these center pipes may expand or contract independently of the outer shell, thus avoiding warping and the creation of stresses that would tear the welds. In addition, the connections along the system are conveniently made with 180° return L's, eliminating the type of stress that tends to crack the welded corners of rectangular boxes or conduits.

The outer shell or frame, comprising the large pipe system 24, is similarly free of rectangular corners and is correspondingly susceptible of long use. In fact, its rugged construction may well permit its lasting indefinitely, i. e., for reuse even if the center section has to be replaced. The welded pipe connections are likewise at localities where a pull occasioned by expansion or contraction is more even than at the corners, and the curvature of the bends is likewise important, in both the outer and center sections, to facilitate coolant circulation.

The flattened shape of the horizontal pipes in the central unit 25 not only provides effective cooling over a greater region between faces of the door, but also contributes substantially to the maintenance in place of the refractory material, in accordance with principles believed to have been unappreciated heretofore. Thus the pipe structure is such that as the refractory softens and even melts because of the extremely high temperatures, a phenomenon occurs that can be described as a shelf formation. More specifically, as the molten or softened refractory flows downward, it comes into contact with and tends to gather upon the horizontal cooling pipes, and by reason of their relatively low temperature, freezes around them. In this manner the pipes are kept covered with refractory material so as to prevent their being locally overheated. At the same time, the flattened pipes, together with the solidified blanket of refractory around each, constitute shelves for supporting the molten or softened material above each section 27, thus tending to hold such material in place.

As will now be apparent, the wicket hole structure is of corresponding special utility in that it is effectively cooled by rapid water flow and yet is of an independently constructed nature, so that it can if necessary be separately replaced, i. e., separately of the remainder of the sinuous central unit. At the same time the design, including the described baffles and vents, is such as to prevent air locking or other conditions conducive to overheating.

Extensive operations for test of doors embodying the invention, in fact doors specifically constructed as shown in the drawings and herein described, have demonstrated exceptional utility.

Over a long furnace run of many heats, the improved door remains fully effective, develops no leaks, and retains much of the original refractory material, with the horizontal cooling pipes completely covered. With a prior brick-lined, tank-cooled construction, warped and leaking doors were an extremely frequent occurrence, causing innumerable furnace delays and requiring millwrights to be working on hot furnaces almost constantly. Thus it will be seen that the door of the present invention permits a great saving of time in furnace operations, and is much safer in use since it is not necessary for repair personnel to be working constantly on hot doors at furnaces filled with molten metal.

It is to be understood that the invention is

not limited to the specific apparatus herein shown and described but may be embodied in other forms without departure from its spirit as defined by the following claims.

5. We claim:

1. A furnace door comprising, in combination, conduit structure defining the periphery of the door and providing a defined, continuous path for flow of coolant around said periphery, the path of said conduit structure being a closed plane figure, disposed in a vertical plane, a backing plate secured to the conduit structure along one face of the latter, to constitute an outer face for the door and to provide a region surrounded by said conduit structure and closed at one side by said plate, said region occupying nearly all of the area of the door, and means in said region, defining further paths for coolant flow, for cooling the portion of the door constituted by said region, 10 said last-mentioned means comprising a multiplicity of horizontal pipe sections, each extending nearly across said region, said sections being interconnected for coolant flow through them in succession, said sections being spaced from each other and from the peripheral conduit but distributively occupying substantially all of said region throughout a plane parallel to said plate, each of said horizontal pipe sections being horizontally flattened at least nearly throughout its 15 length and thereby having a horizontally flat upper surface occupying a substantial part of the depth of said region perpendicular to said plate, and refractory material filling all of the spaces in said region and thereby constituting 20 a body of refractory substantially filling said region and substantially surrounding said horizontal pipe sections, said horizontal pipe sections being closely spaced in a vertical direction to each other, said spacing above each of the afore- 25 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960
2. A furnace door comprising, in combination, a length of pipe defining the periphery of the door and providing a defined, continuous path for flow of coolant around said periphery, a second length of pipe having a substantially smaller cross section than the peripheral pipe and disposed centrally of the door and following a sinuous course to occupy distributively the area defined by the peripheral pipe, said sinuous length of pipe including a plurality of closely spaced parallel horizontal sections disposed in vertical array and each having a flattened configuration providing a larger horizontal than vertical dimension, curved pipe sections connecting said horizontal sections in series at alternate ends for effecting changes of direction of coolant flow therein to follow the sinuous course, means interconnecting said first and second lengths of pipe in series for flow of coolant through them in succession, coolant inlet and outlet fittings connected to said lengths of pipe at one edge of the door, an outer face including a plate having a configuration similar to said periphery and welded tangentially to said first length of pipe, a plurality of studs projecting perpendicularly from said outer face inwardly of the door, and refractory material filling the otherwise empty spaces within said periphery defined by said first length of pipe, said horizontal sections being disposed close enough to each other to cooperate effective-

9

ly with said studs in holding said refractory material in place when the latter becomes fluid.
